THERMOSTATIC VALVE STRUCTURE

John H. Grayson, Lynwood, Calif., assignor to
 Grayson Heat Control, Inc., Lynwood, Calif., a
 corporation of California

Application January 21, 1931, Serial No. 510,075

5 Claims. (Cl. 236—48)

This invention relates to thermostatic valve structures generally, and more particularly, a combination burner and thermostat for gas burning water heaters.

Thermostatically controlled water heaters are usually equipped with a gas burner in the heating chamber below the tank and a thermostat separate and distinct from the burner installed in the side wall of the tank and arranged to control the opening and closing of a valve for delivering gas to the burner. This arrangement naturally entails considerable labor and ingenuity in the assembling of the heater so as to get the thermostat properly connected with the burner and, of course, necessitates a lot of pipe connections that are not only unsightly but are apt to give trouble through leakage when the heater is in service. Obviously, the arrangement referred to meant high cost. It is therefore the principal object of my invention to provide a thermostatic valve structure adapted to be embodied in a burner to form a combination burner and thermostat as a unitary assembly. This facilitates assembling because one operation is all that is required to assemble the burner on a heater with its thermostatic valve structure as a part thereof, and the number of fittings and pipe connections required is reduced to an absolute minimum. However, while the invention is concerned with the embodiment of the thermostatic valve structure in a burner, it should be understood that the same is capable of use independently of a burner and is furthermore not limited to use on a water heater or any other specific gas appliance.

The invention is more fully described herein-after as reference is made to the accompanying drawings in which—

Figure 1 is a fragmentary view of a water heater equipped with a combination burner and thermostat made in accordance with my invention;

Fig. 2 is a vertical, longitudinal section through the unit showing the same substantially full size;

Fig. 3 is a view similar to Fig. 1 showing a unit of modified or alternative construction;

Fig. 4 is a vertical section through the unit shown in Fig. 3; and

Fig. 5 is an isolated view of a part adapted for use with the unit shown in Fig. 4, illustrating a different construction.

Similar reference numerals are applied to corresponding parts throughout the views.

Referring first to Figs. 1 and 2, the combination burner and thermostat unit, indicated by the reference numeral 10, is illustrated as applied to

a conventional water heater, the tank of which is shown at 11 having the usual heating chamber 12 below the bottom 13 with which the usual flue 14, extending upwardly through the tank, has communication so as to carry off the waste products of combustion. A plate 15 closes the bottom of the chamber 12 except for the central opening 16 to admit the primary and secondary air to the burner to support combustion, and, of course, the usual legs 17 are provided for the support of the heater at the desired elevation with respect to the floor. A sight hole or window is provided at 18 in the side wall of the chamber 12 and at 19 I have illustrated a baffle whose purpose is to deflect the flame of the burner upwardly into more intimate contact with the tank bottom 13 for efficient heating. The use of such a baffle is, however, unimportant because with certain burners and special designs of water heaters it would not be necessary. As stated above, it was heretofore common practice to provide a burner in the chamber 12 separate and distinct from a thermostat installed through the side wall of the tank at some point above the heating chamber, and, of course, also separate and distinct from a valve forming part of the same unit with the thermostat and arranged to be controlled thereby to control the delivery of gas to the burner. That arrangement was unsatisfactory for numerous reasons, as was outlined above. For one thing, the thermostatic valve unit was necessarily fully exposed on the side of the heater as well as the pipe connections leading to and from said unit. Then, too, the pipe leading from the valve had to be extended down the side of the tank and under the tank to the burner, which meant numerous pipe fitting operations and aside from detracting from the appearance of the heater meant just that many more places where there was apt to be gas leakage. In the case of a snap action thermostat, where a pilot light is used in connection with the burner, there was, of course, that additional set of pipe connections that had to be taken care of between the valve and the burner. These various objections are avoided by the unitary construction of the burner and thermostat provided in accordance with my invention, as will now be described.

The burner 20 and thermostat 21, together with the valve 22 controlled by the thermostat, are made up as a unitary assembly, namely, the unit 10 previously referred to. The burner 20 comprises a cast tubular body 23 having its upper end threaded, as at 24, to permit mounting the same in a spud or bushing 25 in the tank bottom 110

13. The body 23 is internally threaded at its upper end, as at 26, so that the tubular element 27 of the thermostat 21 can be threaded therein whereby to seal the burner from the tank and utilize the burner as a support for the thermostat. The thermostat extends directly upwardly centrally in the tank so as to be subjected to the heating of the water. The thermostat has the usual plug 28 closing the upper end of the tube 27 and in this plug the rod element 29 of the thermostat has its upper end threaded. The tube 27 is of copper or other material having a high coefficient of expansion, whereas the rod 29 is of invar or any other suitable material which has practically no expansion or contraction with temperature change. In that way, the rod is given upward movement in the expansion of the tube and downward movement in the contraction thereof for a purpose which will soon appear. It is obvious that the installation of the thermostat in this novel manner permits the use of a thermostat of any desired length. That is to say, the thermostat can, by virtue of the present arrangement, be made as long as need be without regard to the diameter of the tank, which otherwise had to be taken into consideration. The mounting of the burner suspended from the bottom of the tank provides good support therefor and it is obvious that the assembling of the burner on the tank takes care of the installation of the thermostat in the same operation. The saving in labor cost which results from this novel arrangement must be self-evident.

The valve 22 has its hollow body preferably cast as an integral part with the body 23 whereby to provide the valve chamber 30 directly below the burner to be placed in direct communication with the burner when the valve proper, shown at 31, is opened. The valve 31 cooperates with a valve seat ring or spider 32 which, like the valve, is suitably of brass, and for that reason may be assembled in the cast iron valve body simply with a press fit. The ring 32 provides a central guide opening 33 through which the reduced lower end 34 of the rod 29 projects. The rod 29, it will be observed, extends through the burner 23 the full length thereof whereby to provide an operating connection between the thermostat 21 and the valve 31. The extremity of the reduced portion 34 fits into a socket 35 provided therefor in the valve 31 to communicate movement to the valve against the action of a spring 36. The latter is a tapered coiled compression spring having its small upper end fitting about the boss on the valve in which the socket 35 is provided and having its other end seating in a cap 37 threaded into the valve body. The cap serves as a removable closure for the chamber 30, and its removal permits removal of the valve for the purposes of cleaning and inspection and also permits adjustment of the thermostat with a screw driver arranged to be entered in the slot 38 provided in the lower end of the rod 29.

In operation, when the temperature of the water in the tank drops sufficiently the contraction of the tube 27 results in downward movement of the rod 29 to open the valve 31. This results in the flow of gas from the valve chamber 30 directly into the burner. The gas issues through jet openings 39 into the nozzles 40, air being entrained with the gas through the openings 41 to produce a Bunsen flame at each nozzle. The gas is delivered to the valve 22 through a supply pipe 42 connected thereto as shown. Holes are provided on opposite sides of the valve body to

permit leading the supply pipe in from either side, and a plug 43 serves to close whichever hole is not used. After operation of the burner for a predetermined time, when the water in the tank attains a predetermined temperature sufficient to expand the tube 27 the requisite amount, the rod 29 is moved upwardly and allows the valve 31 to close under the action of the spring 36. It is evident that by the combination of the valve body with the burner and thermostat in one unit I eliminate all intermediate pipe connections between the valve and burner and accordingly reduce material and labor costs to an absolute minimum. It should also be clear that the combination of the thermostat, burner and valve enables the manufacturer of the unit to ship the same to a plumber for installation in a tank which the latter may have in stock, eliminating the skill required for the manufacture of an efficient automatic water heater, where the two principal devices, namely, the thermostatic valve and burner are separate units, requiring considerable fitting and other assembling operations in the installation thereof.

In passing, attention is called to the boss 44 cast integral with the valve body adjacent the lower end of the burner. A by-pass hole 45 is drilled through the valve seat ring 32 into said boss to establish communication between the valve chamber 30 and a passage 46 communicating with the burner 23 on the other side of the valve. A plug 47 is threaded for adjustment in the outer end of the passage 46 to regulate the amount of gas by-passed through the hole 45 as is thought to be clear from the drawings. A removable cap 48 permits access to be had to the plug when it is desired to adjust the same. The thermostatic valve just considered is one of the graduating type in which the burner relies upon the bypassing of gas to keep it burning with a low flame when the valve is closed. In Figs. 3 and 4, I have illustrated a valve operating with snap action and in that case there is no need for the by-passing of gas to keep the burner lit, but a pilot light is provided in connection with the burner to take care of ignition whenever the gas is turned on under the control of the thermostat.

Referring to Figs. 3 and 4, the unit 10', like the unit 10, consists of the combination of a burner 20', thermostat 21' and valve 22'. In this case, the body 23' of the burner 20' is also threaded at its upper end for suspension from the tank bottom 13 in the manner previously described and has the tube 27 of the thermostat threaded therein at 26 so that the burner constitutes a support for the thermostat and the latter extends upwardly centrally in the tank. The rod 29 of the thermostat extends downwardly through the burner 23' the full length of the latter for cooperation with the valve 22'. The burner is of a special design in which the lower portion of the body is enlarged in a horizontal plane, as appears at 50, and has tips 51 inserted therein to direct the flame therefrom upwardly toward the tank bottom, there being other tips 52 on the other portion of the burner directing their flame horizontally and crosswise with respect to the flame from the tips 51, so as to spread the flame as much as possible to the full diameter of the tank bottom for most efficient heating. With this design of burner there is no need for a baffle such as the one shown at 19 in Fig. 1. The advantages derived by the combination of the thermostat with the burner have been referred to above in the discussion of the unit 10.

The valve 22', as indicated above, is of a snap action type, which dictates the necessity for a pilot burner indicated at 53. This burner forms part of a safety pilot gas cock 54 covered in a copending application, Serial No. 510,886 filed January 24, 1931. The gas supply pipe 42 has communication with the valve chamber 30' in the body of the valve 22' through the cock 54. The construction and mode of operation of the cock 54 is, of course, fully described in the other application and it will, therefore, suffice to state that it has a turn-plug 55 received in the body thereof arranged to be turned by means of a handle 56 to bring its port 57 into and out of communication with the passage through the body. A longitudinal bore 58 is provided in the plug 55 and slidably receives a tube 59 on the outer end of which the pilot burner 53 is mounted and through which the burner is supplied with gas from the cock 54. A bracket 60 fixed on the body of the cock 54 supports a bi-metallic thermostat (not shown) in proximity with the pilot burner and this thermostat has its lower end free and arranged to communicate movement to the tube 59 inwardly to close the port 57 in the event the pilot burner 53 is extinguished. When the port 57 is closed there is, of course, no delivery of gas either to the pilot burner 53 or to the valve chamber 30'. In other words, the device is entirely shut off until the operator attends to the relighting. So long as the pilot burner is lit the thermostat holds the tube 59 retracted with respect to the port 57 and, of course, that allows the flow of gas to the valve chamber 30' as well as to the pilot burner 53. An adjustable plug 61 is provided in the cock 54 to restrict the passage according to the pressure available, so that the burner will operate most efficiently. This much description is thought to be sufficient for an understanding of the safety pilot gas cock, at least for the present purposes.

The valve 22' has the body thereof suitably cast integral with the body 23' of the burner 20' so that when the valve 31' is opened the valve chamber 30' is arranged to be thrown directly into communication with the burner. The advantages of this unitary construction were discussed above in connection with the description of the unit 10. The valve 31' is arranged to be opened and closed abruptly under the control of the thermostat 21' and an actuator mechanism 62 provided between the valve 31' and the end of the rod 29. The mechanism 62 is similar to that covered in my Patent 1,744,465. The mechanism is contained in a bushing 63 threaded in a sleeve 64 which is inserted in the valve body with a press fit. The parts 63 and 64 are cast of brass and, of course, the valve body and the body of the burner are of cast iron. The bushing 63, by virtue of its threaded reception in the sleeve 64, is arranged to be adjusted in the setting of the device by simply removing a cap 65 which constitutes a closure for the valve chamber and threading said bushing one way or the other by insertion of a tool in the ports 70, or in any other recesses provided for the purpose in said bushing. The removal of the cap also permits the removal of the valve 31' for cleaning and inspection. The cap also serves to hold a spring 66 in position behind the valve 31' to urge the same toward its seat 67 on the bushing 63. The bushing 63 not only provides the valve seat but also has the guide opening 68 for the valve stem 69. A series of ports 70 are provided in the bushing around the guide 68 and, of

course, inside the circle defined by the seat 67. The bushing 63, furthermore, constitutes the support for the valve actuator mechanism 62, and the bushing 63, in addition to being adjustable, by virtue of its threaded mounting, is removable for purposes of inspection, cleaning, or replacement of parts of the mechanism 62. In other words, the whole working unit, consisting of the bushing, with its mechanism 62 and valve 31', is quickly and easily demountable. The mechanism 62, in accordance with my Patent 1,744,465, comprises a snap action diaphragm 71 of spring material resting on an annular shoulder formed in the bushing 63 of a certain diameter, resilient levers 72 resting on another annular shoulder in the bushing of a slightly larger diameter and a plunger 73 slidably received in the bushing behind the levers and having an annular shoulder on the face thereof bearing against the back of the levers near the outer ends thereof. The diaphragm 71 is normally convexo-concave and has the inner ends of the levers 72 bearing against the center thereof and arranged to apply pressure to force the diaphragm over dead center, whereupon the diaphragm snaps over to concavo-convex form to open the valve 31' abruptly. The small screw mounted in the upper end of the stem 69 provides an adjustment whereby the desired clearance can be obtained between the diaphragm 71 and the stem 69 so that the valve 31' will not commence to open until the diaphragm is past dead center, at which time, of course, the valve is opened abruptly by the snap action of the diaphragm. It will be observed that holes 74 are provided in the diaphragm 71 and holes 75 in the plunger 73 so that gas can flow through the bushing 63 from the valve chamber 30' to the burner 20' when the valve 31' is opened.

In operation, when the water in the tank drops to a predetermined temperature the contraction of the tube 27 of the thermostat 21' causes downward movement of the rod 29 and when this movement is enough to cause the levers 72 to exert the requisite pressure on the diaphragm 71 the latter is forced past dead center and snaps to reverse curvature and opens the valve 31' for the delivery of gas to the burner. After the burner has operated a certain length of time and heated the water to a predetermined temperature the expansion of the tube 27 causes upward movement of the rod 29 and as soon as this movement is enough to relieve the pressure on the diaphragm 71 to permit it to return to its normal curvature it snaps back and the spring 66 closes the valve just as abruptly as it was previously opened, thereby shutting off the flow of gas to the burner.

In Fig. 5, I have illustrated a slightly different construction of the bushing 63 in which a bushing 63' is formed integral with a cap 65', there being webs 76 interconnecting these parts. The cap 65' has temperature graduations thereon, as indicated at 77. An index mark is provided on the valve body to cooperate with this temperature scale. Then, all that the operator has to do is turn the cap to bring the desired temperature next to the index mark, and, of course, there is no guesswork about the adjustment. Obviously, since the cap 65' will not thread in the body a compressible gasket of rubber or the like will have to be provided encircling the cap in the bore in which the cap fits, so as to prevent gas leakage.

In the above description the burners have all been of the type cooperating directly with the

tank bottom but in the case of water heaters of the percolator type it is obvious that the burner will be mounted on the bottom of the percolator and the thermostat extended upwardly therefrom 5 through the percolator into the tank to serve the same purpose as outlined above. Obviously, the same advantages would result from such an arrangement.

It is believed the foregoing description conveys

10 a good understanding of my invention and the appended claims have been drawn so as to cover all legitimate modifications and adaptations.

I claim:

15 1. A thermostatic valve structure comprising a casing having an inlet chamber and an outlet chamber therein, a bore in said casing between said chambers, a bushing inserted in said bore constituting the partition wall between said chambers, a valve seat provided on said bushing 20 in the inlet chamber, there being ports in said bushing circumscribed by the valve seat, a valve in the inlet chamber for cooperation with said seat, spring means normally urging the valve toward closed position, a bore in said bushing 25 constituting a valve stem guide, a valve stem received in said guide, said bushing having an annular shoulder therein for supporting a valve actuator, a valve actuator in the form of a snap-action disc of spring material resting on said shoulder, said disc being normally substantially 30 convexo-concave in form but arranged when forced over dead center to snap to reverse curvature, whereby to engage the valve stem to open the valve, a plunger slidable in said bushing toward the disc and arranged to communicate 35 amplified movement to the center of the disc for a given movement of the plunger, and a thermostat for communicating movement to said plunger, the disc and plunger each having one 40 or more holes provided therein for the passage of gas from the inlet to the outlet chamber when the valve is opened.

2. A thermostatic valve structure comprising a casing having an inlet chamber and an outlet chamber therein, a valve seat separating the one chamber from the other, a valve in the one chamber for cooperation with said seat, thermostatic means in the other chamber adapted to cause opening and closing of said valve, according to 45 temperature change, and a valve actuator in the last mentioned chamber in the form of a snap-action disc of spring material disposed between the valve and thermostatic means and resting about the edges thereof on an annular shoulder between the inlet and outlet chambers, whereby it constitutes a partition diaphragm 50 separating said chambers, said disc being normally substantially convexo-concave in form but being arranged to be forced over dead center by said thermostatic means to snap to reverse curvature, the aforesaid valve being so disposed with relation to said disc to be opened when the disc snaps to reverse curvature, said valve being otherwise closed, said disc being constructed to permit the passage of gas through it from the inlet chamber to the outlet chamber when the valve is opened.

3. A thermostatic valve structure comprising a casing having an inlet chamber and an outlet chamber therein, a valve seat separating the one chamber from the other, a valve in the one chamber for cooperation with said seat, thermostatic means in the other chamber adapted to cause opening and closing of said valve, according 70 to temperature change, and a valve actuator in

the last mentioned chamber in the form of a snap-action disc of spring material disposed between the valve and thermostatic means and resting about the edges thereof on an annular shoulder between the inlet and outlet chambers, whereby it constitutes a partition diaphragm separating said chambers, said disc being normally substantially convexo-concave in form but arranged when forced over dead center to snap to reverse curvature, the aforesaid valve being so disposed with relation to said disc to be opened when the disc snaps to reverse curvature, said valve being otherwise closed, and a plunger slidably received in said chamber between said disc and thermostatic means and arranged to communicate amplified movement to the center of the disc for a given movement of the thermostatic means, the disc and plunger being constructed to permit the passage of gas from the inlet to the outlet chamber when the valve is opened.

4. A thermostatic valve structure comprising a casing having an inlet chamber and an outlet chamber therein, a bore in said casing between said chambers, a bushing inserted in said bore constituting the partition wall between said chambers, a valve seat provided on said bushing in the inlet chamber, there being ports in said bushing circumscribed by the valve seat, a valve in the inlet chamber for cooperation with said seat, spring means normally urging the valve toward closed position, a bore in said bushing constituting a valve stem guide, a valve stem received in said guide, said bushing having an annular shoulder therein for supporting a valve actuator, a valve actuator in the form of a snap-action element of spring material resting on said shoulder, said element being normally disposed on one side of its dead center but being adapted when forced over dead center to snap to an opposite position, whereby to engage the valve stem to open the valve, and a thermostat for communicating movement to said snap-action element, the snap-action element being constructed so as to permit passage of gas thereby from the inlet to the outlet chamber when the valve is opened.

5. A thermostatic valve structure comprising a casing having an inlet chamber and an outlet chamber therein, a bore in said casing between said chambers, a bushing inserted in said bore constituting the partition wall between said chambers, a valve seat provided on said bushing in the inlet chamber, there being ports in said bushing circumscribed by the valve seat, a valve in the inlet chamber for cooperation with said seat, spring means normally urging the valve toward closed position, a bore in said bushing constituting a valve stem guide, a valve stem received in said guide, said bushing having an annular shoulder therein for supporting a valve actuator, a valve actuator in the form of a snap-action element of spring material resting on said shoulder, said element being normally disposed on one side of its dead center but arranged when forced over dead center to snap to an opposite position, whereby to engage the valve stem and open the valve, a plunger slidable in said bushing toward the snap action element and arranged to communicate amplified movement thereto for a given movement of the plunger, and a thermostat for communicating movement to said plunger, the snap-action element and plunger being constructed so as to permit the passage of gas thereby from the inlet to the outlet chamber when the valve is opened.
